CARD STRIPPING AND FEEDING DEVICE

Francis J. Rouan, Stamford, and Frederick W. Uthenwoldt, Glenbrook, Conn., assignors to Pitney-Bowes, Inc., Stamford, Conn., a corporation of Delaware

Application November 23, 1946, Serial No. 711,890

3 Claims. (Cl. 271—44)

1

This invention relates to a device for use in effecting the intermittent stripping and feeding of the lowermost card from a stack of cards, and is particularly adapted for use with an inserting machine of the character disclosed in Thompson Patent No. 2,384,506.

In said patent, a machine is provided which utilizes a reciprocating ram for the purpose of entering a fold in the lowermost sheet of a stack of folded sheets and moving said folded sheet into the fold of the lowermost folded sheet of another stack of folded sheets, then advancing the two nested folded sheets into an open mouthed envelope.

In accordance with the present invention, the lowermost card of a stack of cards is adapted to be partially stripped from the stack, then be picked up by, and rest upon the surface of the ram during the forward stroke thereof. The ram moves the card within the fold of the first folded sheet, as the ram moves toward a discharge position. The use of a card feeding device with the above named inserting machine considerably increases the utility of the machine.

The disclosure of the present invention therefore, includes part of the inserting machine of the above named patent, which, with features of this invention, provides a primary card stripping operation during the feeding stroke of the ram, the card being moved to an inserting position by the ram on the following forward stroke thereof.

It is the general object of the invention therefore, to combine with a reciprocating card feed member, a card stripping device which will effect partial stripping of the lowermost card from a stack of superimposed cards while the card feed member moves forward to effect an inserting operation, and to effect the pick-up of the partially stripped-card by the card feeding member at the beginning of the following feeding stroke.

With the above and other objects in view, which will appear as the description proceeds, the invention resides in the combination and arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawings, wherein:

Fig. 1 is a skeleton longitudinal sectional view through an inserting machine and includes a portion of the card stripping and feeding mechanism

2

in position at the beginning of a stripping and feeding operation.

Fig. 2 is a view similar to Fig. 1 with the card feeding mechanism in a discharge position;

5 Fig. 3 is an enlarged plan view of a portion of the mechanism shown in Fig. 1, looking at the card supporting and card stripping structure;

Fig. 4 is a longitudinal sectional view taken along the line 4—4 of Fig. 3, after a primary card 10 stripping operation has been completed;

Fig. 5 is a view somewhat similar to Fig. 4, showing the pick-up and feed of the stripped card;

Fig. 6 is a view somewhat similar to Fig. 4, but 15 showing a primary card stripping operation; and

Fig. 7 is a vertical sectional view taken on the line 7—7 of Fig. 4.

In general, cards are stacked in a hopper over the ram at the location of its extreme rearward stroke. The cards are further arranged so that the rearward edge of the lowermost card rests upon a shelf positioned at a higher elevation than the forward edge thereof. While the ram moves forward, during a feeding operation, the lowermost card is stripped from the shelf by stripper mechanism and the rearward edge thereof is positioned in the path of card engaging members on the ram. On the following feeding motion of the ram, the card engaging members engage the 20 rearward edge of the stripped card and feed same to a discharge position.

Referring to the drawings in detail, the inserting machine comprises a casing 10 having a longitudinal central opening 11 through the top thereof to permit free reciprocating motion of a ram 12, in a manner shown and described in the aforesaid Patent No. 2,384,506. In this disclosure only those parts of the inserting machine are shown which are associated with the present invention.

40 Within the casing, a belt 13 is supported upon pulleys 14—14, which pulleys are suitably mounted on shafts 15—15, carried by brackets 16—16. A drive is provided for one of the pulleys in the manner disclosed in the aforesaid patent.

The ram 12 includes a blade 17 mounted on the top of a slidable block 18, which block has sidewaysly disposed tongues 19—19 adapted to slide in grooves 20—20 provided within the inner side walls 21—21 forming the opening 11.

45 A yoke member 22 depends downwardly from the slidable block 18 and has a vertically disposed opening 23 within which a roller 24 extends. The roller 24 is mounted on a bracket 25, which bracket is secured to the outer surface of the belt 13.

Upon rotation of the pulleys in a counter clockwise direction, as viewed from Figs. 1 and 2, the upper reach of the belt will move in the direction of the arrow and carry therewith the bracket 25 with its roller 24, which in turn will effect movement of the yoke 22 in a forwardly direction. The drive is reversed when the belt moves the bracket 25 about the forwardly positioned pulley at the discharge end of the machine.

At one lower corner of the yoke 22, another roller 26 is mounted on a pin 27, which roller is positioned in an operative relation with the upper edge of a track 28 extending substantially the length of the machine. Said track 28 is suitably supported at one end upon a rod 29 and at the other upon a pin 31. The rod 29 is suspended between a pair of levers 32-32, pivotally mounted on studs 33-33. The studs are supported in bearings 34-34 suspended from the top of the casing 10. The pin 31 is fixed to the end of a lever 35, which lever is pivotally supported on a stud 36, mounted in a bracket 37. Said bracket 37 is mounted on the inner forward wall at the discharge end of the casing 10. The lever 35 is normally urged upward by means of a spring 38.

A card supporting hopper 39 is mounted above the ram 12 at the extreme rearward position thereof. Said hopper comprises front and rear walls 41 and 42, and includes sidewardly disposed wall portions 43-43 and 44-44 respectively with supporting feet 45-45 and 46-46. Said feet 45-45 and 46-46 are secured to raised base members 47-47, which members extend within the sidewardly bent portions 43-43 to provide a seat for the forwardly disposed end of the lowermost card of a stack of cards, contained within the walls 41 and 42 of the hopper 39. A shelf 48, extending inwardly from the rearward wall 42, is positioned at a higher level than the surface of the base members 47-47, thereby elevating the rearward end of the lowermost card relative to the forward end thereof. A card supporting finger 40, Fig. 6, fixed to the wall 42, extends beneath the lowermost card, midway between the sides thereof, with its top surface in alignment with the top surface of the ram. By means of said finger, a flat surface is maintained across the lowermost card.

Card feeding fingers 49-49 project above the ram 12 and include downwardly disposed portions which extend through openings 51-51 in said ram and are secured to the ram supporting block 18 by screws 52-52. The upper projecting ends of the card feed fingers 49-49 extend forwardly to provide hook-like portions for gripping the rearward end of the pre-stripped card. To permit said fingers 49-49 to pass beneath the stripped card on the return stroke of the ram, an inclined lug may be provided for each finger as indicated at 49a-49a.

Stripping means is provided for the purpose of stripping the lowermost card from the shelf 48 and depositing same on the surface of the base members 47-47. Said stripping means comprises a pair of rotatable discs 53-53 positioned at a predetermined distance a part within the side edges of the lowermost card. Inasmuch as the two discs and the driving mechanism therefor are the same, only one will be described.

As best seen in Fig. 7, stripper disc 53 is rotatively mounted upon a stub shaft 54, the disc having a hub 50, to which a detent wheel 60 is

fixed. The shaft 54 is fixed within a bracket provided by a downwardly extending wing 55 formed on the base member 47. Said disc 53 is also provided with four serrated or toothed portions 56, the teeth of which are preferably pointed to adapt same to effect slight penetration of the card during engagement therewith, and to thereby provide effective stripping of the lowermost card from the shelf 48. A gear segment 57 is secured to a ratchet wheel 58, and the unit is freely rotatable about the stub shaft 54.

The gear segment 57 is adapted to be driven by means of a toothed segment 59, formed on the end of an arm 61, which arm forms a part of the lever 32 and is adapted to be rocked therewith during the forward stroke of the ram, when the roller 26, on the yoke 22, moves along the track 28, and causes said track to be depressed from the position shown in Fig. 1 to the position shown in Fig. 2. The latter action causes the lever 32 to rock in a clockwise direction, thus moving segment 59 upwardly, from the position shown in Fig. 1 to the position shown in Fig. 2, and effecting rotation of the gear segment 57 in a counter-clockwise direction. Rotation of the gear segment 57 effects rotation of the ratchet wheel 58, the teeth 58a of which engage a pawl 62 carried by the disc 53. During each upward driving motion of the toothed segment 59, the ratchet wheel 58 is driven and one of the teeth 58a will engage the pawl 62 to effect rotation of the disc 53 a quarter revolution. To maintain the disc 53 in an adjusted position and permit the return of the segment 59, a detent pawl is provided, as indicated at 65, which engages a notch 63 in the detent wheel 60, as shown in Fig. 4.

Means is provided to prevent more than one card from advancing either during a primary stripping operation or during a feeding operation. Said means comprises a pair of frictional obstruction members 68-68 which are positioned in the path of the forward ends of the lowermost cards. Inasmuch as said obstruction members are alike, only one will be described.

The frictional member 68, such as rubber for example, is mounted within a holder 69, which holder is pivotally mounted at 71 on a bracket 72. The bracket 72 is mounted on the forward hopper wall 41 and has an extension 73 overhanging the holder 69. Within said extension is a screw 74, which is adapted to be adjusted so that the lower end thereof will be positioned at a predetermined distance from the upper surface of the holder 69. A spring 75 is mounted over the lower projecting end of said screw, between the upper surface of said holder and the lower surface of a lock nut 76. By means of said spring, pressure is applied to the holder 69 to urge the frictional obstruction member 68 downwardly against the surface of the base member 47. Upward movement of the holder 69 is restricted to a distance provided by the position of the end of the screw 74.

In the operation of the device, cards C are stacked in the hopper 39, preferably filling the hopper. The other hoppers of the inserting machine, as noted in the aforesaid patent, are stacked with folded sheets, and one hopper at the discharge end of the machine will contain the envelopes which are to be stuffed.

Assuming that the mechanism is in the position shown in Fig. 1, the drive of the belt 13 in the direction of the arrow will move the bracket 75 22 to the left, as viewed from Fig. 1, and ad-

vance the ram 12 forward through a feeding stroke. The roller 26 on the bracket 22 will move along the track 28 during said feeding stroke to depress said track and effect rocking of the levers 35 and 32 in a clockwise direction. Rocking of the levers 32 will cause the gear segments 59-59 to rock upwardly about the pivot studs 33-33 and rotate the serrated edged discs 53-53 a quarter revolution in a counter-clockwise direction.

As best shown in Fig. 6, rotation of the discs 53-53 will effect engagement of the teeth 56-56 with the lowermost card to strip said card from the shelf 48. Thereupon, the rearward edge of the card is permitted to lie in the path of hook like members 49-49 projecting above the surface of the ram 17, which, during the following cycle of the ram, will engage the said rearward edge of the card and move the card therewith. The card will lie flat on the surface of the ram while the ram moves in a forwardly direction and will be inserted within the open fold of a folded sheet S, Fig. 1, or the ram may move directly into an open mouthed envelope if no folded sheets are in the path thereof. The stuffed envelope is removed after the ram has completed the forward stroke thereof in a manner disclosed in the aforesaid patent.

Having described the invention, what is claimed is:

1. In a device for stripping and feeding the lowermost card from a stack of superimposed cards and comprising, a member having a card engaging portion and adapted to feed a card from a pick-up position to a discharge position, intermittently rotatable stripper means having a frictional portion engageable with the lower surface of the lowermost card to move said card from the stack to the pick-up position, a reciprocating drive for said member, and means associated with said reciprocating drive and connected with the stripper means to actuate said stripper during the card feeding motion of the drive.

2. In a device for stripping and feeding a card from a stack of superimposed cards and comprising, reciprocating mechanism including a member having a card engaging portion and adapted to feed a card from a pick-up position to a discharge position, a rotative stripper frictionally engageable with one exposed face of a card to move said card from the stack to the pick-up position, and means controlled by said reciprocating mechanism to effect the stripping operation of the rotative stripper during the card feeding motion of the reciprocating mechanism.
3. In a device for stripping and feeding a card from a stack of superimposed cards and comprising, reciprocating mechanism including a member having a card engaging portion and adapted and adapted to feed a card from a pick-up position to a discharge position, a rotative stripper frictionally engageable with one exposed face of a card to move said card from the stack to the pick-up position, a lever controlled gear drive connected with said rotative stripper, and means associated with the reciprocating mechanism to effect operation of the lever controlled portion of the gear drive and the consequent stripping of a card during the card feeding motion of the reciprocating mechanism.
